UNITED STATES PATENT OFFICE

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING TRACK-CIRCUIT REGULATOR

Original application filed November 22, 1927, Serial No. 234,985. Divided and this application filed December 12, 1929. Serial No. 413,494.

My invention relates to railway signaling track circuit regulators, and has for an object the provision of novel and improved means for preventing excessive energization of the track relay when the track ballast is dry, and, consequently, has relatively high resistance.

The present application is a division of my copending application filed November 22, 1927, for railway signaling track circuit regulators, Serial No. 234,985.

I will describe one form of track circuit regulator embodying my invention, and will then point out the novel features thereof in claims.

The accompanying drawing is a diagrammatic view showing a track circuit having applied thereto one form of regulator embodying my invention.

Referring to the drawing, the reference characters 1 and 1^a, designate the track rails of a railway track, which rails are divided by insulated joints 2 to form a track section.

This section is provided with a track circuit comprising the rails of the section, a source of current connected across the rails at one point, and a track relay R having a winding connected across the rails at another point. As here shown, the source of track circuit current is a transformer T having its secondary connected across the rails 1 and 1^a, and having its primary connected with a source of alternating current which is not shown in the drawing. A limiting impedance 3 is interposed between the secondary of transformer T and one of the track rails in accordance with usual practice.

In a track circuit of the type just described, it is necessary to so adjust the source of current that it will maintain the normal operating voltage across the relay winding during the lowest value of ballast resistance, that is, during the time of maximum saturation of the ballast with water. When the ballast resistance rises, however, the voltage across relay R will also rise, and this may result in over-energization of the relay with consequent injurious effects unless means are provided to prevent an increase of current in the relay due to increase of voltage across the

track rails at the point at which the relay is connected with the rails.

In accordance with my invention, I provide a regulator connected across the rails adjacent the relay and so adjusted as to conduct current when and only when the voltage across the relay winding rises a given amount above the normal operating value. As shown in the drawing, this regulator comprises two electrolytic cells C¹ and C², each having a tantalum electrode and a lead electrode immersed in a solution of sulphuric acid 6. A cell of this character has a much higher resistance in one direction than in the other direction, and, consequently, it is necessary to oppositely connect two cells in multiple when the source of current for the track circuit is alternating. These cells are of such nature that a gas is evolved when current flows through the cell, and current will not flow through the cell until the potential between the electrodes exceeds a definite value known as "over-voltage". When the applied potential exceeds the over-voltage, the current which flows through the cell is limited only by the internal resistance of the cell, that is,

$I = \frac{E - e}{r}$, in which equation E is the applied potential, e is the over-voltage, and r is the internal resistance of the cell. Considering this equation, it is obvious that when E is a variable between zero and maximum, no current will flow through the cell until E exceeds e, but when E does exceed e, if r is small, the current through the cell will increase very rapidly with increase of E. The combination of electrodes and electrolyte is so chosen that e, the over-voltage of the cell, is slightly higher than the normal operating voltage of the relay R.

It follows that when the ballast resistance is low, no current will flow through the cells C¹ and C², and the relay R will then receive all of the energy transmitted to the relay end of the track section. When the ballast resistance rises, however, current will flow through the cells as soon as the potential across the relay exceeds the over-voltage of the cells. By suitably proportioning the cells to the track circuit characteristics, the cells can be made to prevent any

decided increase in the current through the relay, and so to prevent injurious effects on the relay due to over-energization.

Although I have herein shown and described only one form of track circuit regulator embodying my invention, it is understood that various changes and modifications may be made therein within the scope of the appended claims without departing from the spirit and scope of my invention.

Having thus described my invention, what I claim is:

1. In a railway signaling track circuit of the type comprising track rails, a track relay having a winding connected across said rails, and a source of current also connected across said rails and adjusted to maintain the normal operating voltage across said relay winding during the lowest value of ballast resistance, the combination with the aforementioned instrumentalities of an electrolytic cell connected across said rails and comprising a lead electrode and a tantalum electrode in a sulphuric acid solution, said cell being adjusted to conduct current when and only when the voltage across said relay winding rises a given amount above the normal operating value.
2. In a railway signaling track circuit of the type comprising track rails, a track relay having a winding connected across said rails, and a source of alternating current also connected across said rails and adjusted to maintain the normal operating voltage across said relay winding during the lowest value of ballast resistance, the combination with the aforementioned instrumentalities of two electrolytic rectifiers oppositely connected in multiple across said rails and each adjusted to conduct current when and only when the voltage across said relay winding rises a given amount above the normal operating value.

In testimony whereof I affix my signature.

SAMUEL M. LUCAS.
